UNITED STATES PATENT OFFICE

2,280,591

BUILDING FRAME STRUCTURE

Filip Ludvig Lang, Waxio, Sweden

Application July 12, 1938, Serial No. 218,852
In Sweden July 14, 1937

2 Claims. (Cl. 20—2)

The present invention relates to a building frame structure and has for its object to provide an improved fitting for movably connecting building elements produced in the mill and transported to the place of erection in condition for assembly.

An embodiment of the invention is illustrated in the accompanying drawing.

Figure 1 shows a vertical section of a sill at a corner of a building structure which is provided with a fitting constructed according to the invention.

Figures 2 and 3 are horizontal sections of the upright in the same corner at a distance from the sill and at the sill respectively.

Figure 4 is a perspective of said fitting.

Figures 5 and 6 show a vertical and horizontal section respectively of another embodiment of a corner construction.

Referring to the drawing in detail particularly to Figs. 1 to 4 the sills are indicated by 92, the upright by 93 and the stay by 94. In Figure 4 there is shown a fitting 95 composed of angularly disposed L-shaped parts fitted into central grooves 96 in the end portions of the respective abutting building elements. One sill 92 is turnable around a bolt 97 extending through the sill and through a hole 97a in one part of the fitting. In the same way the upright 93 is turnable around the bolt 98 which traverses the hole 98a of the other part of the fitting. The angular portion of the fitting is received in the groove 96 of the other sill 92 and is secured to said sill by bolts 99 traversing the sill and the holes 97a in the fitting. The stay 94 is fixed to the upright 93 by bolt and nut 100. In order that one shall be able to adjust the stay to the correct position, its end portion resting against the sill is made displaceable. This displaceability is obtained by a plate 101 which is adapted to be displaced in the sill and locked in the desired position. The stay is turnably fixed to the plate by the bolt 101a, the said bolt projecting into a groove 102 in the stay. The plate extends into a groove 103 of the sill having slots in the side walls thereof through which project bolts 104, the latter also passing through the plate so that the plate can be moved to and fro and fixed in the desired position.

In the corner construction shown in Figures 5 and 6 the sills are indicated by 119 and the upright by 120. One sill is turnably fixed to the legs of a U-shaped plate 121 by a bolt 122. The web of the plate is positioned in a central slit 125 in the other sill. Into this slit 125 a plate 124 is fitted which also is positioned in a slit 123 in the upright 120. The two plates are fixed to one another and to the last mentioned sill by the bolt 126. Moreover, the plate is preferably fixed to the sill, into which the plate has been fitted, by a second bolt 127. The upright is turnable around a bolt 128 inserted through the plate 124. In this embodiment of the invention the plate 124 and contiguous web of the U-shaped plate form a plane flange constituting one part of the fitting and the legs of the U-shaped plate form spaced flanges constituting another part of the fitting.

Having now described my invention, what I claim as new and desire to secure by Letters Patent is:

1. In a building frame structure for walls, floors and roof of portable buildings, three frame elements, one of said elements being slotted, a fitting of angular form and including two L-shaped parts disposed perpendicularly to one another, a bolt securing the angle of the fitting in the slot of said slotted element, and bolts pivotally connecting the two other of said frame elements to each of the shorter legs of the fitting whereby the several elements may be folded together in compact relation.

2. In a building frame structure for walls, floors and roof of portable buildings, three frame elements, a fitting including a plane flange and spaced flanges projecting perpendicularly from the plane flange, a bolt pivotally connecting one of said elements to the plane flange, a second bolt pivotally connecting another of said elements to the spaced flanges, the third element having a slot therein, and a bolt securing one of said flanges in said slot, said fitting connecting together one end each of the several elements whereby the latter may be folded together in compact relation.

FILIP LUDVIG LANG.
